AUTOMOBILE COOLER

**Theron L. Hedgpeth, Annapolis, Calif., assignor to
Carl Lynch, Kingman, Ariz.**

Application January 29, 1952, Serial No. 18,273

Term of patent 14 years

(Cl. D14—6)

To all whom it may concern:

Be it known that I, Theron L. Hedgpeth, a citizen of the United States, residing at Annapolis, county of Sonoma, State of California, have invented a new, original, and ornamental Design for Automobile Cooler, of which the following is a specification, reference being had to the accompanying drawing, forming a part hereof.

Fig. 1 is a side elevational view of an automobile cooler showing my new design.

Fig. 2 is a side elevational view of the automobile cooler of Fig. 1 as seen from the side opposite that shown in Fig. 1.

Fig. 3 is a perspective view of the automobile cooler of Fig. 1.

Fig. 4 is a top plan view of the automobile cooler of Fig. 1.

Fig. 5 is an end elevational view of the automobile cooler of Fig. 1 as seen from one end

thereof; and Fig. 6 is an end elevational view as seen from the end opposite that shown in Fig. 5.

Fig. 7 is a bottom plan view of the automobile cooler of Fig. 1.

I claim:

The ornamental design for an automobile cooler, as shown.

HERON L. HEDGPETH.
